UNITED STATES PATENT OFFICE.

THOMAS E. BURLINGAME, OF DELAVAN, ILLINOIS.

TONGUE-SUPPORT.

SPECIFICATION forming part of Letters Patent No. 372,740, dated November 8, 1887.

Application filed July 18, 1887. Serial No. 244,623. (No model.)

To all whom it may concern:

Be it known that I, THOMAS E. BURLINGAME, a citizen of the United States, residing at Delavan, in the county of Tazewell and State 5 of Illinois, have invented certain new and useful Improvements in Tongue-Supports; and I do hereby declare that the following is a full, clear, and exact description of the invention, which will enable others skilled in the art to 10 to which it appertains to make and use the same.

This invention relates to tongue-supports for vehicles.

The object of the invention is to produce a tongue-support which shall be much stronger 15 and less liable to become injured or dislodged by jolting than tongue-supports as heretofore made. Furthermore, the object is to produce a tongue-support whereby the height of the tongue may be regulated or adjusted rapidly 20 and with but little manipulation of the parts.

With these objects in view the invention resides, essentially, in a tongue-support consisting in a spring attached to the axle or other portion of the frame of the vehicle, 25 which moves with the tongue, and a hanger attached to the frame or box of the vehicle and sustaining the spring in proper operative position. Furthermore, the invention resides in various novel details of construction where- 30 by the objects of the invention are attained.

I have illustrated the invention in the accompanying drawings, in which—

Figure 1 is a plan view showing the application of my tongue support, and Fig. 2 is a 35 side elevation. Fig. 3 is a detail view showing the means for adjusting the height; and Fig. 4 is a detail view showing the end of the spring and the means for retaining it in place upon the tongue.

40 In the drawings, A represents the axle of a vehicle, upon which are mounted the wheels B. To this axle is secured, by a king-bolt in the usual way, a bolster, L.

C represents a tongue, which is attached to 45 the hounds D in the usual manner by the pin F, and is capable of a limited vertical movement. The tongue is held in the desired position by means of the curved spring J, one end of which is formed with an eye, O, se- 50 cured to the axle by means of a bracket, N, firmly attached to the axle, and having a bolt which passes through the eye in the spring. The outer end of the spring bears upon the

under side of the tongue and supports it in its proper position. The tongue is provided 55 at the point where the spring bears with a guide or shoe, Q, which protects the tongue against wear caused by the friction of the end of the spring on the tongue. The spring is supported at or near its center by a stirrup, I, 60 which is attached at its upper end to the bolster or other portion of the vehicle elevated above the tongue a sufficient distance. It is desirable that the upper end of the stirrup be attached in such manner as to be allowed both 65 a vertical and a horizontal movement, in order to be capable of moving with the tongue. To accomplish this the ends of the stirrups are formed with eyes, through which pass a bolt or pin mounted in the end of a bar, H, which bar 70 is connected to the bolster by the bracket in such manner as to have a free horizontal movement. Thus, as the ends of the stirrup are connected to the pin G in such manner as to permit a vertical movement, the stirrup is 75 free to move with the tongue. The stirrup is attached to the spring by means of the plate J', having a slot, and the bolt P. Thus it will be seen the height of the pole may be changed at will by sliding the plate and by securing it 80 in place by the bolt.

Having thus described my invention, what I claim as new, and desire to secure by Letters Patent, is—

1. A tongue-support consisting of the spring 85 bearing at its outer end upon the tongue, the stirrup connected to the bolster and provided with the bracket whereby it is attached to the bolster, and the plate having the eye receiving the stirrup and the slot receiving the bolt, 90 whereby its position may be regulated, sub-stantially as described.

2. A tongue-support consisting of the spring J, connected to the axle and bearing against the tongue, the stirrup provided with the 95 bracket for connecting it to the bolster, and the plate J', provided with the eye for the re-ception of the stirrup and with the slot, and the bolt passing through the spring and the plate, substantially as described. 100

In testimony whereof I affix my signature in presence of two witnesses.

THOMAS E. BURLINGAME.
